UNITED STATES PATENT OFFICE.

CHARLES KINGSTON WELCH, OF COVENTRY, ENGLAND.

DESIGN FOR A METALLIC WHEEL-RIM.

SPECIFICATION forming part of Design No. 29,990, dated January 10, 1899.

Application filed August 30, 1898. Serial No. 689,869. Term of patent 14 years.

To all whom it may concern:

Be it known that I, CHARLES KINGSTON WELCH, engineer, a subject of the Queen of Great Britain, residing at Park House, Coventry, England, have invented and produced a new and original Design for a Metallic Wheel-Rim, of which the following is a specification.

In the drawings referred to herein, forming a part of this specification, Figure 1 is a transverse section, and Fig. 2 a perspective view, of a wheel-rim embodying my new design.

According to my new design, a metallic wheel-rim A for a pneumatic tire is provided with tubular flanges B, each of which is in the shape of an ellipse, with the major axis (represented by the dotted lines $x\ x$ in Fig. 1) inclined outwardly with respect to the vertical central plane (represented by the dotted line $y\ y$ in Fig. 1) of the rim. The whole of the inner and upper side b of these elliptical flanges—*i. e.*, the side adjacent to the tire—from the inner extremity b' , where the inex- tensible edge of the tire-cover will rest, to the outer extremity b^2 is thus available for the side portions near the edges of the tire-cover to bear against when such portions are pressed outwardly by the perpetual lateral deformation of the tire, which takes place at a point near the ground during the revolutions of the wheel while in contact with the road. The outer and under side b^3 of the ellipse does not project farther from the central plane $y\ y$ of the rim than does the outer extremity b^2 of such ellipse, so that no greater width is given to the rim than is useful for stiffening the edges thereof, and I obtain the maximum

amount of width of the rim internally with the minimum amount of width externally.

In another application filed August 30, 1898, Serial No. 689,870, I have shown a design for wheel-rims, in which tubular flanges having a generally elliptical conformation with the major axes inclined outwardly with respect to the vertical central plane are present; but the present improvement is distinguished from that referred to in this, that in the present case the inner and outer sides of the tubular flanges conform substantially to the curves of a true ellipse, the two halves of which on opposite sides of the major axes are symmetrical, whereas in the rim shown in application Serial No. 689,870 the two halves of the ellipse are unsymmetrical in that while the outer sides of the flange conform to the curve of a true ellipse the inner sides are of a different curvature, the outer extremity b^2 of each inner side being wider and flatter, while the portion near the inner extremity b' of said side is inclined inwardly to a greater extent than if it followed the contour of a true half ellipse, a more pronounced recess being thus formed at the point b' .

What I claim is—

The design for a metallic wheel-rim as herein shown and described.

In testimony whereof I have hereunto set my hand, in presence of two subscribing witnesses, this 19th day of August, 1898.

CHARLES KINGSTON WELCH.
